UNITED STATES PATENT OFFICE.

DANIEL S. KIMMERLE, OF SAN FRANCISCO, CALIFORNIA, ASSIGNOR TO KIMMERLE BROS., A COPARTNERSHIP CONSISTING OF DANIEL S. KIMMERLE, LARNED T. KIMMERLE, AND BILLY F. KIMMERLE, ALL OF SAN FRANCISCO, CALIFORNIA.

HOIST.

Application filed October 26, 1927. Serial No. 223,760.

This invention relates to a hoist which is particularly adapted for use in conjunction with portable wrecking cranes and the like.

The object of the present invention is to generally improve and simplify the construction and operation of hoists of the character described; to provide a gear-driven hoist drum in which gear reduction drives of different ratios may be obtained proportional to the load to be lifted; to provide a hoist having two drums with a common gear reduction drive for driving either drum; to provide means whereby power from the reduction gear drive may be transmitted to drive either drum; to provide means for locking the drums against rotation in one direction to support a load; and further to provide a hand brake to allow lowering of a load when one of the drums is disengaged. The hoist is shown by way of illustration in the accompanying drawings in which:

Fig. 1 is a side elevation of a wrecking crane showing the hoist connected therewith,

Fig. 2 is an end view of the hoist,

Fig. 3 is a plan view of the hoist,

Fig. 4 is a longitudinal section of the small drum and the clutch and gear cooperating therewith.

Referring to the drawings in detail and particularly Fig. 1, A indicates a base or other suitable support on which is mounted a mast B supported in the usual manner by stays or the like indicated at 2. The mast carries a boom arm C, a block D, sheaves 3 and 4, and the mast similarly carries sheaves as indicated at 5 and 6, there being double sets of sheaves at the points 5 and 6. The hoist forming the subject matter of the present application is generally indicated at E. It is provided with two drums indicated at F and G. The small drum F carries a cable 6 which passes over the sheaves 5 and 6 and which is attached to the upper end of the boom as at 7 so as to raise and lower the boom. The drum G carries a cable 8 which also passes over the sheaves 6 and 5 and then over the sheaves 4 and 3, the block D, and being finally secured at the point 9. The general crane structure and the method of arranging the sheaves and reaving the cables forms no part of the present application, but is merely illustrated so that the function of the hoist will be clearly understood. The hoist

proper consists of a frame generally indicated at H. This frame is suitably secured on the base member A and it is provided with bearing members such as indicated at 10—10 and 11—11 in which are journaled shafts 12 and 13. These shafts extend crosswise of the frame H and the drums F and G are supported thereby, being freely rotatable thereon. Fixed to the shaft 13 by key or otherwise is an elongated driving pinion 14. Fixed to the shaft 12 by key or the like is a gear 15 and a pinion 16, and formed integral with the drum G or secured thereto is an intermeshing gear 17; also fixed on the shaft 12 is a grooved collar 18 and engaging therewith is a forked end 19 of a shifting lever 20. This lever is adapted to assume one of the two positions indicated in Fig. 3 and when shifted from one position to another it transmits a longitudinal movement to the shaft 12 and the gears 15 and 16. The driving pinion 14 is sufficiently long to maintain mesh with the gear 15 regardless of the position it assumes but the pinion 16 when shifted with the shaft 12 either meshes with the gear 17 or is moved completely out of gear for purposes herein-after to be described.

By referring to Fig. 4, it will be noticed that one end of the drum F is enlarged as indicated at 21 and that jaw clutch teeth 22 are formed interior thereof. It will also be noted that a jaw clutch member 23 is secured on shaft 12 and that when shaft 12 is moved longitudinally, the clutch member 23 will move into or out of mesh with the cooperating member 22. This is important as the clutch members 22 and 23 serve the function of freeing or securing the drum F with relation to the shaft 12. The drum F is secured against longitudinal movement when shaft 12 is shifted, this being accomplished by forming an annular groove 24 on the enlarged end of the drum into which projects a stationary guide or retaining arm 25. The enlarged end of the drum is also provided with ratchet teeth 26 which are engaged by means of a spring actuated pawl 27. This is also important as it serves the function of locking the drum F against rotation in one direction when a load is to be supported. The drum G which is freely rotatable on shaft 13 is also provided with ratchet teeth. These are clearly shown in Fig. 2, and it will there be noted that the teeth are of the internal type as in

dicated at 29. A pawl 30 cooperates therewith and as such normally secures the drum against rotation in one direction and a load is thereby supported. The drum G is extended as indicated at 31 and this extended portion is surrounded by a friction or brake band 32 which is actuated by means of a brake lever 33, said lever being provided with a pawl 34 which engages ratchet teeth 35 to secure the brake lever when in braking position. Pawl 30 which cooperates with the internal ratchet teeth 29 is provided with a pin 36. This pin is engaged by a pivotally mounted lever 37 on the upper end of which is formed a cam surface 38. When lever 37 assumes the position shown in Fig. 2, pawl 30 will assume locking position and when the lever 37 is swung to a substantially vertical position, the cam surface 38 engages the pin 36 and the pawl is raised to released position, this position being assumed when a load is to be lowered by brake action, lever 37 being moved from one position to another by merely being kicked or pushed over by the foot of the operator. In actual operation, if it is desired to raise or lower the boom C, it is only necessary to shift the gears 15 and 16 to assume the dotted line position shown in Fig. 3. When this position is assumed jaw clutches 22 and 23 engage. If shaft 13 is rotated by means of a hand crank or the like as indicated at 40, power will be transmitted through the pinion 14 and gear 15 to rotate shaft 12 and power will in turn be transmitted through the jaw clutch 22 and 23 to rotate the drum F. The boom arm may thus be raised or lowered to assume any position desired, pawl 27 being held out of engagement with the ratchet teeth 26 when lowering the boom. When raising the boom the pawl is thrown back into engagement with the ratchet teeth, thus securing the boom when a desired raised position is obtained. If the block D is connected with a load and it is desired to lift the same, gears 15 and 16 are shifted to the full line position shown in Fig. 3 and shaft 13 is again rotated. Power will then be transmitted through the gear 14 to rotate gears 15 and 16 and as gear 16 will then mesh with the gear 17, drum G will be rotated at a materially reduced gear ratio and a heavy load may be lifted. If a comparatively light load is handled, it is only necessary to transfer the crank 40 from the shaft 13 to the shaft 12. The power will then be transmitted directly through the gear 16 to the gear 17 and the drum, still at a reduced gear ratio. After a load has been lifted to a desired height, it is obvious that it will be held by the pawl 30. If it is desired to lower the load, drum G is locked by tightening the brake band 32. Lever 33 is then swung to vertical position to release the pawl 30 and the brake band is then slightly released by the lever 33 and the load may thus be fric-

tionally lowered. The hoist here shown may, of course, be used wherever desired, but it is particularly adapted for wrecking cranes such as here illustrated. The single gear reduction drive employed may transmit power to either drum and at different ratios so that practically any load desired may be handled. The mechanism employed is exceedingly simple to operate and as the structure as a whole is substantial and rigid, it may be handled by practically any individual whether mechanically skilled or otherwise. The shifting lever 20 may be secured in either of the positions shown in Fig. 3 by any suitable means. In the present instance, however, an ordinary latch such as indicated at 20^a is illustrated, this latch engaging one or another of a pair of recesses formed in the top of the frame as indicated at 20^b.

While certain features of the present invention are more or less specifically described, I wish it understood that various changes may be resorted to within the scope of the appended claims. Similarly, the materials and finishes of the several parts employed may be such as the manufacturer may decide or varying conditions or uses may demand.

Having thus described my invention, what I claim and desire to secure by Letters Patent is:—

1. A hoist of the character described comprising a frame, a pair of interspaced shafts journaled crosswise of the frame, a drum on each shaft and free to rotate thereon, an elongated spur gear pinion secured on one shaft, a spur gear secured on a second shaft, a gear secured to the drum on the first-named shaft and adapted to mesh with a spur gear pinion on the second-named shaft, and means for rotating the first-named shaft to transmit power through the gears to rotate the drum on the first-named shaft.

2. A hoist of the character described comprising a frame, a pair of interspaced shafts journaled crosswise of the frame, a drum on each shaft and free to rotate thereon, an elongated spur gear pinion secured on one shaft, a spur gear secured on a second shaft, a gear secured to the drum on the first-named shaft and adapted to mesh with a spur gear pinion on the second-named shaft, means for rotating the first-named shaft to transmit power through the gears to rotate the drum on the first-named shaft, and means whereby the pinion on the second-named shaft may be moved out of engagement with the gear on the drum so that power may be transmitted from the first-named shaft through the gears to rotate the second-named shaft and the drum thereon.

3. A hoist of the character described comprising a frame, a pair of interspaced shafts journaled crosswise of the frame, a drum on each shaft and free to rotate thereon, an elongated spur gear pinion secured on one shaft, a spur gear secured on a second shaft, a gear secured to the drum on the first-named shaft and adapted to mesh with a spur gear pinion on the second-named shaft, means for rotating the first-named shaft to transmit power through the gears to rotate the drum on the first-named shaft, and means whereby the pinion on the second-named shaft may be moved out of engagement with the gear on the drum so that power may be transmitted from the first-named shaft through the gears to rotate the second-named shaft and the drum thereon.

gated spur gear pinion secured on one shaft, a spur gear secured on the second shaft, a gear secured to the drum on the first-named shaft and adapted to mesh with a spur gear pinion on the second-named shaft, means for rotating the first-named shaft to transmit power through the gears to rotate the drum on the first-named shaft, means whereby the pinion on the second-named shaft may be moved out of engagement with the gear on the drum so that power may be transmitted from the first-named shaft through the gears to rotate the second-named shaft and the drum thereon, and a clutch on the second-named shaft cooperating with the drum mounted thereon, said clutch cooperating with the pinion gear on said shaft in such a manner that when the pinion meshes with the gear which is secured to the drum on the first-named shaft, a driving connection between the drum on the second-named shaft and the clutch is broken and when the gear pinion on the second-named shaft is moved out of mesh with the gear on the drum, the clutch will engage the drum on the second-named shaft to rotate the same.

4. A hoist of the character described comprising a frame, a main driving shaft journaled crosswise thereof, a second driving shaft journaled crosswise thereof, a main drum freely rotatable on the first shaft, a secondary drum freely journaled on the sec-

ond-named shaft, a gear secured to the main drum, a reduction gear drive adapted to transmit power to said gear and drum, a 35 shiftable gear in said drive movable into and out of mesh with said gear, a shiftable clutch cooperating with the drum on the second shaft and movable in unison with said shiftable gear, said clutch being out of mesh with 40 the drum when the shiftable gear is in mesh with the drum gear, and being engaged with the drum when the shiftable gear is out of mesh with the gear on the drum.

5. A hoist of the character described comprising a frame, a pair of interspaced shafts journaled crosswise thereon, a free drum on each shaft, a gear secured to one drum, a gear secured to the shaft on which the drum is mounted, a pair of gears secured to the 50 other shaft, a jaw clutch on said same shaft and cooperating with the drum which is mounted on said shaft, and means whereby the gears and the clutch on the second named shaft are moved longitudinally in unison so 55 as to maintain the clutch and drum disengaged when the gears on the second-named shaft mesh with the drum gear and the gear on the first-named shaft and so as to engage the clutch and the drum when the gears on 60 the second-named shaft are moved out of mesh with the drum gear on the first-named shaft.
